R. H. MacINNES

TERMINAL HUB FOR THE BURNERS OF ELECTRIC RANGES

Filed Sept. 14, 1923

INVENTOR

ROBERT H. MACINNES,

BY *H. H. MacInnes*
ATTY.

UNITED STATES PATENT OFFICE.

ROBERT H. MACINNES, OF HAMILTON, ONTARIO, CANADA, ASSIGNOR TO D. MOORE COMPANY, LIMITED, OF HAMILTON, ONTARIO, CANADA.

TERMINAL HUB FOR THE BURNERS OF ELECTRIC RANGES.

Application filed September 14, 1923. Serial No. 662,709.

To all whom it may concern:

Be it known that ROBERT H. MACINNES, a subject of the King of Great Britain, residing at Hamilton, in the county of Wentworth and Province of Ontario, Canada, has invented certain new and useful Improvements in Terminal Hubs for the Burners of Electric Ranges, of which the following is a specification.

10 My invention relates to improvements in terminal hubs for the burners of electric ranges and consists essentially of a refractory insulation hub partially recessed into the bottom surface of the burner, and 15 through the core of which extends a conductor bolt forming the terminal of the lead wire; a bearing shoulder formed upon the hub, and a cap adapted to fit over the terminal and suitably grooved to fit over the 20 bearing shoulder which together with said cap constitutes a bearing for the lead wire spaced from its terminal.

The principal objects of the invention are to provide a strong and substantial terminal for the lead wires of an electric burner with the provision of a bearing for the lead wires at a suitable distance from their terminals and at a point where they are insulated and not stripped at their ends where 25 attached to the terminals, to avoid breaking by flexing at their point of connection with the terminals.

A further object is to provide means for protection of the terminal so that nothing of a foreign nature can come in contact therewith.

A still further object is to provide such a device which may be readily removed for inspection or replacement of the parts if required.

Another object is to provide a device of the class described which will be simple, durable, efficient, and inexpensive to manufacture.

These, together with other objects may be attained by the construction, combination, and arrangement of the parts as will be hereinafter more fully described, illustrated in the accompanying drawing, and pointed out in the claims hereunto appended.

Referring to the drawings:

Figure 1 is a bottom view of a portion of a burner showing the terminal hub with the cap removed;

Figure 2 is a bottom view of a portion of a burner showing the terminal hub with the cap in place;

Figure 3 is an enlarged cross sectional side elevation of a portion of a burner in inverted position showing the hub also in cross section; and,

Figure 4 is a side elevation of a portion of a burner and the hub in inverted position.

Similar reference characters refer to similar parts throughout the several views.

The portion of the electric burner to which the terminal hub is secured is indicated on the drawings by A, and the hub by B. The burner is recessed as indicated by 2 in Figure 3 to receive a portion of the hub, such recess being irregularly formed and the adjoining surface of the hub being correspondingly formed so as to prevent rotary movement of the latter upon its axis. A terminal bolt 3 extends through the burner A from one of the resistance wiring grooves 4, and through the core of the hub B, and a thimble shaped cap C is fitted to the outer surface of said hub and through the core of which also extends said terminal bolt. The outer end of said cap is recessed as indicated by C' to contain a suitable nut 5 which is threaded on the end of the terminal bolt 3 to tighten the entire assembly. Upon the outer surface of the hub B is formed a bearing shoulder 6 and the cap C is correspondingly grooved to fit it, as favorably shown in Figure 4. In the outer surface of the shoulder 6 is formed a groove which together with a similar groove in the adjoining surface of the cap C constitutes an outlet 7 and bearing for the lead wire 8 which passes therethrough and is secured to the terminal bolt 3 by the nuts 9.

By so forming a bearing for the lead wire spaced from its actual terminal, any possible flexing of the lead wire will not tend to loosen it or break it away from the terminal.

The end of the resistance wiring 10 is brought through holes 11 in the burner A from the grooves 4 in the opposite side thereof, and carried along grooves 13 in the bottom of the burner from whence it is taken through small holes 14 in the hub and secured to the terminal bolt 3, as shown in Figure 3.

There has thus been provided a simple

and efficient device of the class described and for the purpose specified.

Having now fully described my invention, what I claim and desire to secure by Letters Patent, is:—

1. In a terminal hub of the class specified, the combination with an electric burner, of a refractory insulation hub partially recessed into the burner and having a core, 10 a hollow cap of refractory insulation material positioned against the outer surface of said hub and having a core in the head portion thereof, a terminal bolt passed through the burner and through the cores in said 15 hub and cap, said hub and cap having jointly a passage for a lead wire to the terminal bolt, and jointly forming a bearing therefor.
2. In a terminal hub of the class specified, the combination with an electric burner, of 20 a refractory insulation hub secured to the burner, a hollow cap of refractory insulation material removably secured to the hub, a terminal confined within said cap and communicating with a resistance wiring, said 25 hub and cap having jointly a passage for

a lead wire to said terminal and jointly forming a bearing therefor.

3. In a terminal hub of the class specified, the combination with an electric burner, of 30 a refractory insulation hub secured to the burner, a hollow cap of refractory insulation material removably secured to the hub, a terminal confined within said cap and communicating with a resistance wiring, and a 35 bearing shoulder formed on the edge of said hub and having a groove in its outer surface, said cap being arched in its side to conform to said bearing shoulder, the arched portion of the cap having a groove which jointly with the formerly mentioned groove forms a passage 40 for a lead wire, to said terminal, said shoulder jointly with said cap forming a bearing for said lead wire.

In testimony whereof I have affixed my signature.

ROBERT H. MACINNES.
